UNITED STATES PATENT OFFICE.

THOMAS W. GLINES, OF WASECA, MINNESOTA.

NON-COMBUSTIBLE WICK FOR HEATING AND COOKING STOVES.

1,178,850.

Specification of Letters Patent. Patented Apr. 11, 1916.

Application filed July 15, 1915. Serial No. 40,093.

To all whom it may concern:

Be it known that I, THOMAS W. GLINES, a citizen of the United States, residing at Waseca, in the county of Waseca and State 5 of Minnesota, have invented certain new and useful Improvements in Non-Combustible Wicks for Heating and Cooking Stoves, of which the following is a specification.

This invention relates to wicks, especially 10 non-combustible wicks for use on heating and cooking stoves when saturated with kerosene or analogous fuel.

The primary object of the invention is to provide an asbestos wick that comprises 15 a series of sheets of asbestos spaced to provide a porous and a looser structure than the ordinary asbestos wick; which may be accomplished by separating the asbestos sheets by combustible material and then this combustible material as the last step in the process of making the completed wick.

Various other objects and advantages will become apparent during the continuance of the following description.

25 Referring to the drawings: Figure 1 is a view in longitudinal section of a wick constructed in accordance with my invention, illustrating the application thereof. Fig. 2 is a view in top plan, and Fig. 3 is a view 30 in elevation of one of the non-combustible sheets used in the construction of the wick.

In the drawings, a wick tube 1 is provided which is of the usual configuration and includes the usual perforations. The lower 35 terminal of the tube is turned upwardly in parallelism with the body to provide an annular channel which is adapted to receive the lower end of the wick in a manner hereinafter described.

40 The wick, in its present embodiment, primarily includes a plurality of sheets 2 of non-combustible material, as asbestos, having other sheets of combustible material, such as a vegetable fabric interposed therebetween. Each sheet may be of an oblong 45 configuration whereby when flexed an annulus will be provided for the reception into wick tube 1, as shown in Fig. 1. After the several sheets have been arranged in proper

relation they may be fixed together as indicated in Fig. 3; although this method is an entirely arbitrary feature. All of the sheets may then be subjected to the action of a liquid whereby the primarily frangible sheets 2 may be readily flexed and positioned 55 in place in the wick tube 1. The entire wick structure may then be thoroughly dried by action of a hand torch or the like and subsequently treated in a bath of kerosene or other hydrocarbon until saturated. I then ignite 60 the wick, preferably out of doors where the smoke will not bother, which will cause the complete carbonization of the combustible layers 3 thereby creating a wick of open construction and one wherein the oil will permeate more freely. By providing a wick of this nature, it is obvious that the residue of the oil (generally a tarry substance) will not collect so freely about and between the 65 layers of asbestos. However, when such 70 residue or tarry substance does accumulate, the wick may be again burned out in the nature aforesaid and the life of the same practically renewed.

It will be understood that the above description and accompanying drawings comprehend only the general and preferred embodiment of my invention and that various minor changes in details of construction, proportion and arrangement of parts may 75 be made within the scope of the appended 80 claims without sacrificing any of the advantages of my invention.

I claim:—

1. A wick comprising a plurality of sheets 85 of non-combustible material separated by a sheet of carbonized combustible material.

2. A wick comprising a plurality of sheets of asbestos having sheets of carbonized combustible material interposed therebetween 90 thereby providing an open and porous structure.

In testimony whereof I affix my signature in presence of two witnesses.

THOMAS W. GLINES.
